Primary Examiner — Karen S Acker*Assistant Examiner* — Wendy L Arminio(74) *Attorney, Agent, or Firm* — Erin Collins(57) **CLAIM**

The ornamental design for a patterned wipe, as shown and described.

DESCRIPTION

FIG. 1 is a perspective view of a patterned wipe showing the claimed design;

FIG. 2 is a top plan view thereof;

FIG. 3 is a bottom plan view thereof; and,

FIG. 4 is a side view thereof.

The broken lines depict portions of the patterned wipe that form no part of the claimed design.

1 Claim, 3 Drawing Sheets(56)
